UNITED STATES PATENT OFFICE

WILLIAM KELSO, OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA

UNCOUPLING MECHANISM

Application filed October 4, 1926. Serial No. 139,403.

My invention relates to uncoupling mechanism for actuating the lock of a car coupler. While mechanism constructed in accordance with the present invention is particularly well adapted for association with the standard D-coupler having a top operated lock, it may be employed with couplers of other types as well.

The principal object of the invention is to construct such a mechanism of a few simple parts which may be easily assembled and disassembled and which cooperate to produce a reliable, efficient and easily operated device.

The primary feature of the invention, generally stated, consists in constructing the mechanism with an uncoupling lever involving a transversely extending shaft member and a crank member rotatably mounted thereon, the shaft and crank members being detachably interlocked and the shaft member being journaled in a plurality of laterally spaced relatively movable bearing members.

A further feature of the invention consists in forming the uncoupling lever of relatively rotatable members one of which is a transversely extending shaft having a rigidly attached operating handle and one of which is formed as a crank for cooperating with the lock of the car coupler, the crank member being provided with an eye for receiving the shaft member and the latter being bent at its inner end so as to maintain the crank member in assembled position on the shaft as well as to constitute means for actuating said crank member.

Other features of the invention relating to advantageous structural forms and arrangements of parts will hereinafter appear.

In the drawings illustrating a preferred embodiment of the invention the scope whereof is pointed out in the claims,

Figure 1 is a plan view of an uncoupling mechanism involving the invention, showing its relation to a car.

Figure 2 is an end elevation of the construction illustrated in Fig. 1.

Figure 3 is a detail sectional view on the line 3—3, Fig. 1.

Figure 4 is a detail view, partly in plan

and partly in section, of the movable uncoupling lever bearing and the base on which it is mounted, a portion of the uncoupling lever being also shown.

Figure 5 is a detail view, partly in elevation and partly in vertical section, of the parts shown in Fig. 4.

Figure 6 is a side elevation of the mechanism, looking inwardly towards the coupler.

Figure 7 is a view, partly in side elevation and partly in vertical section, of a modified form of the invention.

Figure 8 is a front elevation of the construction shown in Fig. 7.

Figure 9 is a front elevation of another modified form of the invention.

The car coupler 1 illustrated in the drawings is of the well known top operated standard D-type wherein the locking block for the knuckle is moved to unlocked position by a lock lifter 2 which also functions as a lock-to-the-lock for preventing accidental unlocking of the coupler.

The mechanism for actuating the coupler locking mechanism consists of a transversely extending revoluble uncoupling lever involving a shaft member 3 upon which is movably mounted a crank member 4 for cooperating with the lifter 2 of the coupler locking mechanism.

Both members of the uncoupling lever are preferably formed from round bars. At one end the crank member 4 is provided with a transversely extending portion 5 which projects through and is slidably and revoluble within the opening in the upper end of the lock lifter 2, while at its other end it is preferably formed with an eye 6 which receives the shaft member 3. At its outer end the shaft member is fashioned with a downwardly projecting operating handle 7 and at its inner end it is preferably bent so as to extend forwardly and then under the crank member 4 and then upwardly, as indicated at 8, 9 and 10, respectively. This manner of forming the adjacent ends of the uncoupling lever parts permits the crank member 4 to have a limited rotation with respect to the shaft member 3, thereby permitting the latter to assume its normal position while the

coupler locking mechanism is in unlocked position. It also permits the crank member to shift its angular position laterally, thus enabling it to have a limited universal movement with respect to the shaft member 4. Moreover, means are thereby provided for effecting an unlocking movement of the crank member 4 when the shaft member 3 is actuated for uncoupling and, in addition, the uncoupling lever members are interlockingly connected when the parts are in assembled relation.

The uncoupling lever is revolvably mounted upon the car by means of a plurality of laterally spaced relatively movable bearings in which the shaft member 3 is journalled, the inner bearing member 11 preferably being rotatable on an axis extending substantially normal to the axis of rotation of the shaft member, and the outer bearing member 12 being rigidly bolted or riveted to the car end sill. The movable bearing member 11 is provided at its inner end with an upwardly projecting apertured lug 13 for receiving the shaft member 3, the walls of the aperture being rounded, as indicated at 14, to prevent the shaft member and movable bearing from binding on each other when shifting their angular positions. The bearing 11 may be advantageously mounted on the car by providing it with an integral downwardly projecting pivot pin or trunnion 15 having oppositely projecting locking lugs 16 at its lower end, and by securing to the car end sill an anchor bracket or base plate 17 formed with an aperture 18 for receiving the pivot pin 15, the aperture being so elongated as to permit the locking projections 16 to enter and be withdrawn only when the rotatable bearing member 11 is turned substantially ninety degrees from its normal position. By this means the movable bearing 11 is detachably connected to the anchor bracket 17 and is interlocked therewith when the parts of the mechanism are in assembled relation.

The outer bearing bracket 12 in which the shaft member 3 is journalled is preferably provided with an upwardly extending bearing lug 19 for receiving the shaft member just inwardly of the operating handle 7 and it is also formed with an upwardly projecting lug 20 constituting a stop which cooperates with the handle portion of the shaft member 3 to prevent outward lateral shifting of the uncoupling lever. Inner lateral shifting of the lever is, of course, prevented by the bearing lug 19. The bearing lug is open at the rear to permit assembly of the uncoupling lever therewith, a cotter 21 being employed to prevent disassembly of the lever.

The modified form of the invention illustrated in Figs. 7 and 8 is the same as that heretofore described except that the movable bearing in which the shaft member 3 is journalled is designed to be mounted on the end

of the car body rather than upon the car end sill. In this construction the movable bearing is fashioned as a link 22 having at its lower end an eye 23 for receiving the shaft member 3 and provided at its upper end with an eye 24 for receiving a supporting hook 25 firmly secured to the car body.

Figure 9 illustrates a construction in which the uncoupling lever 26 is formed as a unitary member having an operating handle 7 at the outer end and a crank portion 4 at its inner end. This construction is otherwise the same as that shown in the principal figures of the drawings and accordingly, as in the case of the modified form of the invention illustrated in Figs. 7 and 8, corresponding parts have been indicated by like reference numerals.

The mechanism may be assembled by placing the movable bearing 11 upon the shaft member 3 and then mounting the crank member 4 upon the latter, after which the bearing 11 is turned about ninety degrees from its normal position and its pivot pin 15 entered in the opening of the anchor bracket 17. The bearing member 11 is then turned toward normal position so as to interlock with its supporting bracket and the uncoupling lever is shifted laterally so as to cause the inner portion 5 of the crank arm member to enter the opening at the upper end of the lock lifter 2. When this has been accomplished the shaft member 3 is positioned in the outer bearing lug member 19 and the cotter 21 is inserted, thus completing the assembly.

I claim:

1. In uncoupling mechanism for car couplers, the combination of an uncoupling lever for actuating the locking mechanism of a car coupler, said lever being provided at its inner end with a crank for cooperating with the coupler locking mechanism and having an operating handle at its outer end together with a shaft portion rigidly attached to said handle and extending transversely of the car, and a plurality of laterally spaced bearing members in which said shaft portion is journalled, the inner of said bearing members being rotatable on a fixed axis extending substantially normal to the axis of rotation of said shaft and disposed between said crank and said operating handle, and the outer of said bearing members being rigidly connected to the car body and being provided with a stop cooperating with said handle to prevent outward lateral shifting of said lever.

2. In uncoupling mechanism for car couplers, the combination of an uncoupling lever involving a transversely extending rotatable shaft member and a crank member rotatably mounted on said shaft member and adapted to cooperate with the coupler locking mechanism, said shaft member being journalled in a plurality of laterally spaced relatively movable bearing members, one of said bearing members being horizontally rotatable on a

fixed pivotal axis disposed between said crank member and the outer end of said rotatable shaft.

3. In uncoupling mechanism for car couplers, the combination of an uncoupling lever involving a transversely extending revoluble shaft and a crank member journalled thereon and adapted to actuate the coupler locking mechanism, said shaft member being provided at its outer end with an operating handle and being bent at its inner end so as to provide means for limiting sliding movement of the crank member in the direction of length of the shaft and also means for actuating said 10 crank member, and a plurality of relatively movable bearings in which the shaft member is journalled, one of said bearing members being horizontally rotatable on a fixed pivotal axis disposed between said crank member and 15 said operating handle.

4. In uncoupling mechanism for car couplers, the combination of an uncoupling lever involving a transversely extending revoluble shaft member and a crank member mounted 20 thereon with capability of limited rotation with respect thereto so as to permit the shaft member to assume its normal position while the coupler locking mechanism is in unlocked position, said shaft member being provided 25 at its outer end with an operating handle and being provided at its inner end with means forming an interlocking detachable connection to said crank member, a plurality of bearing means in which the shaft member is 30 journalled, and means cooperating with said shaft member for preventing outward movement of the latter in its direction of length when the parts are in assembled relation, one of said bearing members being rotatable on 35 a vertical axis disposed between said crank 40 and said operating handle.

5. In uncoupling mechanism for car couplers, the combination of a transversely extending uncoupling lever involving a shaft member and a crank member, said shank member being revoluble and having a journal portion constituting its axis of revolution, and said crank member being provided with arms extending at an angle to each other and 45 having an eye for receiving said journal portion of said shaft member, the shaft and crank members having a limited relative rotation permitting the shaft member to assume normal position while the coupler locking mechanism is unlocked, and a plurality of relatively movable bearing means spaced along the shaft member and in which the shaft member is journalled, the said bearing means which is nearer said crank member being 50 pivotally movable on a vertical axis, said shaft member being provided at its outer end with an operating handle and being bent at its inner end so as to extend forwardly and then downwardly and then under said crank member in the direction of length of said 55 60 65 70 75 80 85 90 95 100 105 110 115 120 125 130

shaft member and then upwardly, whereby the crank member is interlockingly maintained on said shaft member in assembled relation thereto.

In testimony whereof I affix my signature. 70
WILLIAM KELSO.
